UNITED STATES PATENT OFFICE.

ERNEST P. SPENCER, OF GRAMPIAN, PENNSYLVANIA.

CARTRIDGE-RELOADING MACHINE.

Application filed December 2, 1925. Serial No. 72,775.

This invention relates to cartridge reloading machines and has for its object the provision of a novel device by means of which various sizes and types of center fire rifle cartridges may be decapped, recapped and reloaded with powder and the necessary projectile.

An important object of the invention is to provide a machine of this character in which 10 the various movably mounted plunger elements for performing the different operations are not only adjustable in accordance with the size or sizes of the cartridges to be worked upon but also interchangeable so 15 that the one machine may be used for performing the various operations, it being consequently unnecessary to have separate implements such as punches or the like for initially removing the exploded primer or 20 cap.

Another object of the invention is to provide a machine of this character in which the parts are so arranged as to insure a straight line movement of the plungers 25 which act upon the cartridge case or shell and the projectile in contradistinction to other and well known type of devices which have a scissors-like movement which results in inaccuracy in the positioning of the projectile within the case as well as the location 30 of the priming cap, the movable plungers of the present device being all arranged in axial alignment and remaining in such position regardless of the movement thereof 35 toward or from each other, as the case may be, under the influence of the actuating levers.

A further object of the invention is to provide a machine of this character embodying 40 automatically acting extractors which engage with the rim of the cartridge case or shell for withdrawing the loaded shell from the machine subsequent to the loading operation, the loaded shell dropping gravitationally from the mechanism without it being necessary to resort to manual operation.

Still another object of the invention is to provide a device of this character having an 45 adjustment whereby the projectile may be caused to enter the shell or case to a greater or less extent depending to a certain extent or degree upon the dimensions of the projectile with respect to the shell or case, the 50 type or nature of the cartridge itself, and which might be a shelf, table or the like,

other circumstances which may enter into the equation.

Still another object is the provision of a machine of this character so constructed and arranged that the open end of the shell or 60 case may be crimped about the projectile, or not, as preferred, this likewise depending upon the nature of the cartridge.

Other objects and advantages such as comparative simplicity and cheapness in 65 manufacture, easy in operation, efficiency and durability in service, together with the general improvement in the art, will become apparent during the course of the following detailed description taken in connection with 70 the accompanying drawing, in which:

Figure 1 is a side elevation of the machine, a portion of the supporting table or stand being in section.

Figure 2 is a horizontal sectional view 75 taken on line 2—2 of Figure 1.

Figure 3 is a detail plan view of the base plate.

Figure 4 is a vertical longitudinal section through the lower portion of the machine 80 showing the ejector mechanism and the remaining portions of the device used for decapping an exploded shell.

Figure 5 is a cross section taken on the line 5—5 of Figure 4.

Figure 6 is a view similar to Figure 5 but showing the gate member in open position.

Figure 7 is a longitudinal vertical sectional view taken through the upper portion 90 of the machine in the act of applying a new primer or cap.

Figure 8 is a detail sectional view with the shell of the cartridge shown in elevation.

Figures 9 and 10 are detail plan views of the swinging gate.

Figure 11 is a vertical longitudinal sectional view through the upper portion of the machine showing one form of mechanism 100 for inserting the projectile.

Figure 12 is a detail view of one portion of the device.

Figure 13 is a longitudinal section illustrating a modification of the means for inserting the projectile, and

Figure 14 is a detail view.

Referring more particularly to the drawings, the numeral 1 designates a support

and upon which the entire mechanism, to be described is mounted. This support is provided with an opening 2 for the accommodation of certain of the parts of the apparatus or machine.

Mounted upon the top of the support 1 and secured thereto, as for instance by means of bolts 3 or the like, is a plate 4 constituting the base of the machine, this plate being provided centrally with a hole 5 and being provided at opposite sides of its center with other holes 6 within the latter of which are secured spaced parallel vertically extending rods 7 which may be formed in one piece or any desired number of sections and which carry, at their upper ends, a cross member 8 held in position as for instance by means of nuts 9 screwed onto threaded extensions 10. Near their lower portions, the rods 7 carry a transverse element 11 held in place by nuts 12. A cross piece 13 is also mounted upon the upright rods 7 at a point immediately above the plate 4, and secured to the plate 4 at one end thereof is a handle member 14 for a purpose to be described. It should also be mentioned that the lower ends of the upright rods 7 are threaded and that one carries a clamping nut 15 located in the opening 2 beneath the plate 4 and that the other carries a cap member 16 which is forked, bifurcated or otherwise constructed for the accommodation of a link or links 17 pivotally connected therebetween as shown at 18 and pivotally connected at 19 with an operating lever 20 spaced from but cooperating with the handle 14 and adapted to be squeezed toward the same as will be explained hereinafter.

At their central portion the cross members 11 and 13 are provided, respectively, with tubular guides 21 and 22 respectively within which is slidably mounted a plunger 23 having a forked lower end 24 pivotally connected at 25 with the lever 20. Obviously, owing to the provision of the link or links 17, there will be no binding at the pivot point 25 and nothing to interfere with the sliding movement of the plunger. At opposite sides, the plunger 23 is longitudinally slotted as indicated at 26, and located within the slot are elongated strips 27 notched as indicated at 28 so as to constitute ejectors adapted to engage with the rim of a cartridge or with a flange or rim on an auxiliary plunger member, to be described, for the purpose of moving the cartridge case, loaded cartridge or auxiliary plunger, as the case may be, downwardly when the lever 20 is moved downwardly upon the completion of certain operations to be described. Obviously, the strips 27 must be prevented from longitudinal displacement as for instance by means of the elements indicated at 29, and embracing the plunger 23 to-

gether with the strips 27 constituting the ejectors is a split spring ring 30. Screwed into the upper end of the plunger 23 is a tapered screw 31 which acts to expand the ejectors and make them conform to or correspond with the sizes of the shells to be reloaded.

Rotatably mounted upon one of the rods 7 is what may be called a gate member 32 slotted as indicated at 33 so as to be engaged upon the other upright rod, a latch device 34 being provided for the purpose of holding the gate in position engaging the second mentioned upright rod. The open position is well illustrated in Figure 6 while the closed position is disclosed or illustrated in Figure 5. This gate member is provided centrally with an upstanding internally threaded tubular projection 35 within which may be screwed a barrel or chamber member 36 within which is slidably mounted a plunger rod 37 having a flanged end 38 with which the extractor strips 27 may engage for providing an operative connection between the plunger 23 and the rod 37. At its upper end, the rod 37 is formed with a threaded socket 39 within which is screwed a plunger rod 40 which carries an upwardly extending spring pressed pin device 41 capable of being used for the purpose of removing an exploded primer cap from a shell in a manner to be described. The shell is represented by the letter A, the constricted end thereof is represented by B, and the head, grooved or flanged in the customary manner, is likewise illustrated but by the letter C.

Stationarily mounted upon the upright rods 7 is a transverse member 42 engaging against shoulders 43 on the rods and carrying a pair of set screws 44 or the like which pass therethrough or thereinto and through slots 45 in a pair of plate members 46 which are slidably mounted upon the top of the transverse member 42 and which have concaved and ribbed or grooved confronting edges adapted to clampingly engage against the flanged head C of the cartridge case from which an exploded priming cap is to be removed and into which a new cap is to be inserted. Obviously, the adjustability of the plate 46 is to enable the device to accommodate and work upon cartridges of different diameters.

Above the uppermost cross member 8, one upright rod 7 carries a member 47 which is forked, bifurcated or otherwise formed and with which is or are pivotally connected a link or links 48, at the point 49, the link or links being in turn, pivotally connected at 50 with a lever 51 which preferably extends in the same direction as the lever 20.

Pivotally connected with the lever 51 at an intermediate point, as indicated at 52 are links 53 which are in turn pivotally con-

ected, at 54, with the upper end of a plunger 55 which carries a die 56 located in axial relation to the plunger 40 and which is provided for the purpose of applying a new priming cap to the cartridge shell or jacket. Attention is invited to the fact that the cross member 42 is provided with an arcuate or curved slot 57 opening out to one edge so as to facilitate the engagement of a cartridge case or shell therein with the flanged end portion of the shell engaged with the slidably adjustably mounted plate 46 as above described. This detail is illustrated in Figure 9 of the drawings.

15 At its underside, the transverse member 32 is formed with threaded sockets 58 for the purpose of effecting connection or mounting of certain elements to be described hereinafter.

20 In the operation up to this point, it will be observed that when it is desired to remove the exploded priming cap from shells, the shells are successively treated in identically the same manner, each shell being inserted in the slots 57 in the transverse member 42 with the grooved head or end thereof engaged by the adjustable plates 46. The shell is thus held stationary. The various plunger devices 37 and 40 must of course be connected in a manner illustrated and as described above and initially the position of the lever 20 is such that the shell or jacket A will be clear of the plunger 40. However, after the shell has been placed in position and is supported by the transverse member 42 in a depending position, it will be observed that the uppermost plunger member 40 will be located immediately below the shell or jacket so that when the lever 20 is moved upwardly by squeezing it toward the handle 14 the plungers 23, 37 and 40 will act to move the plunger 40 upwardly through the shell or jacket, the pin structure 41 acting to remove the exploded cap.

35 40 After the exploded cap has been removed, a new cap is placed in position at the upper end of the shell or jacket and the handle member 51 is moved downwardly whereupon the plunger 55 carrying the die 56 will act to force the new cap into proper position at the end of the shell or jacket in an obvious manner.

45 In order to adapt the device for reloading a shell which has been equipped with the new priming cap, the guide member 36 is removed from the tubular portion 35 of the transverse member 32 and replaced by a guide member 59 screwed into the tubular portion 35 and maintained, in exactly the same manner as in the first instance, in the desired adjusted position by means of an adjusting or lock nut 60. The tubular guide 59 is of the proper size to accommodate the particular type or style of cartridge, and it is intended, in actual practice, that the ma-

chine be provided with a kit or plurality of these guides 59 in order to accommodate and work upon cartridges of different types and sizes. The guide 59 is of course provided with a chamber or bore 61 conforming exactly to the style or type of cartridge, and is also provided with a bore 62 for the accommodation of the proper type of projectile D to be inserted within the shell or casing. Furthermore, the bore 62 may be so constructed at its juncture with the bore 61 as to exert a crimping action upon the open end of the shell or jacket in case such is desired.

50 When the device is used for reloading or for inserting a projectile within a cartridge shell or jacket, use is made of a plate member 64 located beneath the transverse member 32 and pivoted at one end by means of a stud or screw 65 passing through the plate member 64 and engaged within one of the threaded sockets 58 in the underside of the cross member 32. The plate member 64 is formed at one side with a hook 65a adapted to be engaged with a similar stud or screw 66 which is threaded into the other one of the threaded sockets 58 in the underside of the cross member 32. The purpose of this plate 64 is to support the cap end of the cartridge shell or jacket as clearly indicated in Figure 11.

55 The central opening in the cross member 42 contains or is provided with a bushing 67 of such size as to accommodate a plunger device 68 which has a reduced extension 69 slidably engageable through the bore 62 in the tubular guide 59. It should be stated that the upper end of this tubular guide carries a cap-like member 70 screwed thereonto, and consequently adjustable, which cap member is held in the desired position by means of a lock or jam nut 71 likewise screwed onto the upper end of the tubular guide 59. The upper end of the cap or cup members 70 is apertured for the passage of the reduced end 69 of the plunger 68 as will be readily apparent. At its upper end, the plunger 68 is formed with a reduced extension 72 designed to be connected with the plunger 55 subsequent to the removal of the die member 56, the size or diameter of the die 56 and the extension 72 being identical in order that connection may be readily made and in order that the parts will be interchangeable as is of course necessary for reasons of economy and convenience. Obviously, the bushing member 67 may be held in place by a pair of plates 73 quite similar to the plate members 46 used for holding the shell or casing during the decapping and recapping operation, the only difference being that the confronting concaved ends or edges of the plate member 73 need not be grooved or ribbed as is necessary for holding the grooved or ribbed end of the cartridge shell

or jacket. Of course adjustment is effected in exactly the same manner owing to the provision of the screws 44 above described, these same screws being provided in connection with this portion of the apparatus.

Assuming that the desired number of cartridge shells or jackets have been decapped and recapped, the chamber member 36 is detached from the gate member 32 and is replaced by the chamber member 59, the particular member 59 employed depending of course upon the size of the cartridge shell or jacket. The plungers 40 and 37 are removed and the plunger member 68 is engaged with the plunger 55. A shell to be reloaded may be initially filled with the desired amount of powder and the gate or plate member 64 swung on its pivot 65 out of obstructing relation to the lower end of the chamber member 59 so that the cartridge, with the projectile placed lightly in the open end thereof, may be moved upwardly into the chamber member 59, or else the projectile may be inserted from the top, whichever is preferred, the position being accurate in either instance. The swinging plate 64 is then swung into its normal position with the hook at the end thereof engaging upon the screw 66, this plate member acting as a support for the flanged or head end of the cartridge. The operator then grasps the lever 51 and moves it downwardly so that the plunger 68, which has its lower end recessed as indicated, will engage against the projectile D and force the same downwardly into the cartridge to the desired extent. After this is done, the gate or plate member 64 is swung away whereupon the lever 20 is moved upwardly so that the ejectors carried by the plunger 23 will engage the flange at the end of the loaded cartridge and remove it from the chamber member 59. This operation is of course repeated for each and every shell to be reloaded.

In Figure 13 I have illustrated a slight modification in which the chamber member 59^a corresponding to the chamber member 59 has a threaded extension 75 upon which is screwed a cap member 76 through the upper end of which is screwed a plunger 77 locked in place by a suitable jam nut 78. In the operation of this form, the case is loaded from the underside of the tubular guide only and is not in any way connected with the upper plunger 55 or 68. In loading by using chamber 59^a, case is charged with powder, projectile entered in case and then entered in guide chamber 59^a, swinging member 32 closed, and case forced into place by plunger 23 operated by lever 20, projectile swinging against threaded stop screw 77 threaded into cap member 76 the element 77 extending into member 59^a. The principal difference between the two forms is, that in the first the projectile is seated from the top by up-

per plungers 68, 69, 55, operated by lever 51, whereas in the second the guide loads from the bottom, the projectile and case being forced together by lever and plungers 20 and 23.

From the foregoing description and a study of the drawings, it will be apparent that I have thus provided a comparatively simple and inexpensive machine for the purpose specified, which will operate most efficiently and which will effect a great saving of time, labor and material in the reloading of cartridge shells of the center fire type.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:

1. In a device of the character described, upright supporting members, transverse elements carried by said upright supporting members, a lever operated plunger vertically movably mounted through certain of the lower ones of said transverse elements, a vertically movable lever operated plunger slidably mounted through certain of the upper transverse elements, a gate member carried by the upright members, and means carried by said gate member for receiving and holding a cartridge shell, said means comprising a chambered element having a chamber therein corresponding to the size and shape of the cartridge to be loaded, means carried by the gate member and normally engaging beneath the chamber member for supporting a cartridge shell therein, and means connected with the upper plunger movable into the chamber member for forcing a projectile into the shell.

2. In a device of the character described, upright supporting members, transverse elements carried by said upright supporting members, a lever operated plunger vertically movably mounted through certain of the lower ones of said transverse elements, a vertically movable lever operated plunger slidably mounted through certain of the upper transverse elements, a gate member carried by the upright members, and means carried by said gate member for receiving and holding a cartridge shell, comprising a member having a chamber of a size and shape to conformingly receive a cartridge and the projectile therefor, a movably mounted support carried by the gate member beneath the chambered member for supporting the cartridge therein, and means connected with the second named plunger adapted to enter the chamber member for forcing the projectile into the shell.

3. In a machine of the character described, a stationary support, upright members carried by said support, transverse elements connecting said upright members, a 5 gate member pivoted upon one upright member and detachably engageable with the other, a guide located at the center of said gate member, means for holding a cartridge within said guide, a lever operated ejector 10 mounted beneath said gate member and movable toward and from the same, and a lever operated plunger movable into the upper end of said guide.
4. In a device of the character described, 15 a supporting frame, a horizontally swingable gate member pivoted thereto, a guide carried by said gate member having a chamber adapted to receive a cartridge shell and projectile therefor, a pivoted plate element 20 on the underside of the gate member normally acting as a seat for the shell, a longitudinally movable ejector means located beneath said plate and adapted to be engaged with the shell, and a lever operated 25 plunger movable into the upper portion of the guide for forcing the projectile into the shell.
5. In a device of the character described, 30 a supporting frame, a horizontally swingable gate member pivoted thereto, a guide carried by said gate member having a chamber adapted to receive a cartridge shell and projectile therefor, a pivoted plate element 35 on the underside of the gate member normally acting as a seat for the shell, a lon-
- gitudinally movable ejector means located beneath said plate and adapted to be engaged with the shell, and a lever operated plunger movable into the upper portion of the guide for forcing the projectile into the shell.
6. In a machine of the character de- 45 scribed, a supporting structure, means mounted within the structure for supporting a cartridge shell, a plunger vertically slid- 50 able through the upper portion, a plunger vertically slid- able through the lower portion in alignment with the first named plunger, said plungers coacting with the shell to de- 55 cap and recap the same, supporting means operable to support the recapped shell, and means operable by the first named plunger 55 for effecting insertion of a projectile into the shell.
7. In a machine of the character de- 60 scribed, an extractor comprising a plunger, means for moving the same, said plunger being provided in opposite sides with longi- 65 tudinally extending slots, strips mounted within said slots and having their end portions formed with heads adapted to engage the flange at the end of the cartridge, and a split resilient band surrounding the plunger and engaging said strips for normally holding them contracted.

In testimony whereof I affix my signature.
ERNEST P. SPENCER.
